CLOTHESLINE REEL

Filed April 5, 1928

Inventor:
Earl C. Warner,

by Joseph W. Harris
M. D.

UNITED STATES PATENT OFFICE.

EARL C. WARNER, OF PHILADELPHIA, PENNSYLVANIA.

CLOTHESLINE REEL.

Application filed April 5, 1928. Serial No. 267,517.

This invention relates to reels of the class generally used for holding clothes lines, but which may also be used for other purposes.

An object of the invention is to provide a durable, yet simple clothes reel, that is protected from the weather, is portable, and that does not too readily unwind when the clothes line is being pulled out.

A further object is to provide a clothes line reel in which the clothes line will not become entangled within the casing.

In the accompanying drawing, which is diagrammatic only—

Figure 1 is a vertical section of the reel, carrying a quantity of clothes line, with the drum in the unwinding position;

Fig. 2 is a broken sectional view similar to Fig. 1, without the clothes line, but with the drum in the winding position;

Fig. 3 is a view in perspective, of the handle;

Fig. 4 is a view of the hook used to engage the handle;

Fig. 5 is a detached view of a disc provided with studs, which serve to engage a movable clutch member;

Figs. 6 and 7 are views of an opened out and cylindrical metal plate, which constitutes the surface of the drum upon which the clothes line is wound;

Fig. 8 is an incomplete view of the front side of the case of the completed reel, showing the handle engaged by the hook; and

Fig. 9 is a detached view showing a step in the assembly with the brake member out of engagement with a wall of the drum.

In Fig. 1, a casing comprising an outer cover 1, and a rear wall 2, suitably fastened with screws or otherwise joined, is provided with a ring or other supporting means 3, and link 4, by which it may be suspended, the link being riveted to the wall 2 at 5. At the center of the rear wall 2 is a socket 6, secured by rivets 7. At the center of the inner wall

45 of the outer cover 1 is a similar socket 8, and on the outside wall of the cover is the hook 9, both hook 9 and socket 8 being secured to the cover 1 by rivets 10. A shaft 23, one end of which is seated in the socket 6, is provided 50 with a shoulder 23^a the shaft projecting slidably through the central drum into the sleeve 27 leaving a space indicated at 32 in Fig. 2, but which space is occupied in Fig. 1.

Within the casing is mounted a drum having side walls 14, 15, and a winding surface 16, the latter consisting of a strip of metal,

see Fig. 6, provided with tongs 16^a, and a semi-circular perforation 16^b at each end; the strip of metal is folded into a cylinder, Fig. 7, the openings 16^b registering as shown. 60 Upon the wall 14 is secured the perforated disc 18, by rivets 19; and upon the wall 15, is secured the perforated disc 20, by rivets 21, the rivets having projecting lugs 21^a for heads. The shaft 23 is then inserted through 65 the perforated disc 18, the shoulder 23^a on the shaft resting against said disc 18; a perforated disc 24, see Figs. 1, 2 and 9, is next placed upon the shaft, and rests in contact with the wall 14; the spring 26 is next placed 70 on the shaft 23, and is followed by the perforated disc 25; the handle 11 is detached from the ferrule 27, and the ferrule placed on the shaft with the ends 27^a, see Fig. 3, resting against the disc 25, Fig. 1. A large 75 headed screw 28, with a small threaded end 28^a, has been secured in the outer end of the ferrule. The strip of metal 16 is folded into a cylinder as shown in Figs. 6 and 7, and its tongs 16^a on the left side are 80 inserted in openings in the wall 14 provided for the purpose, and said tongs bent over, as shown in Figs. 1 and 2. One end of a suitable length of clothes line 17, or other rope, is threaded through the opening 16^b in the cylinder or drum 16, and suitably knotted, as at 85 17^a. The wall 15 is then placed upon the ferrule 27 and the tongs 16^a on the right side of the cylinder 16 are passed through holes provided in the wall 15, and bent over, as shown 90 in Figs. 1 and 2. The spacing ferrule 22 is then placed on the ferrule 27; the rope 17 is next threaded through the opening 1^a in the casing cover 1, after which the cover is placed over the ferrule 27, and the rim edge of the 95 cover secured to the rear wall 2 in any suitable manner. The handle 11 is now placed over the screw end 28^a and the nut 29, see Fig. 1, attached. The reel is now completely assembled. 100

Assuming the rope 17 is completely drawn out, and it is desired to wind it upon the drum within the reel, the handle 11 is disengaged from the hook 9^a, see Fig. 2, whereupon the spring 26 presses disc 25 and lugs 27^a of the 105 ferrule 27, see Fig. 3, are pressed into engagement with the lugs 21^a projecting from the disc 20 on the wall 15, see Figs. 2 and 5; the cooperating lugs 27^a and 21^a constituting a clutch. Upon turning the handle 11 with 110 knob 12, the ferrule 27 is turned and through the engagement of lugs 27^a with lugs 21^a, the

drum is turned, winding up the rope 17. The handle 11 may be turned in either direction. The spring 16 exerts sufficient pressure upon the discs 24 and 25 to keep disc 24 in constant contact with the wall 14 when the handle is disengaged from hook 9^a.

When it is desired to unwind the drum, and draw out the rope 17, the handle 11 is pressed in and engaged by the hook 9^a, see Fig. 1, thereby disengaging the lugs 27^a from the lugs 21^a, releasing the drum, and at the same time increasing the spring pressure upon the disc 24 which in turn more firmly engages the wall 14, and functions as a friction brake, retarding the otherwise easy and rapid unwinding of the rope, preventing the same from becoming entangled. The degree of friction between the disc 24 and wall 14 is controlled by the strength of the spring 16. The discs 24 and 25 may be made of fibre or other material.

The entire construction is simple, efficient and durable, and is portable, and in use it prevents the rope from unwinding and becoming entangled within the casing, due to the spring pressure brake action; while when winding the same spring pressure maintains the clutch lugs 27^a and 21^a in positive engagement.

30 I claim:

1. A clothes line reel comprising a casing,

a shaft, a rotatable drum loosely mounted on said shaft, a spring surrounding said shaft, a friction brake, said brake mounted to frictionally engage said drum, a handle, a clutch, said clutch comprising fixed and movable members, said fixed members attached to said drum, said movable members attached to said handle, a catch on said casing to engage said handle and hold the clutch members out of engagement, said spring pressing said clutch members into engagement upon the release of said handle from said catch.

2. A clothes line reel comprising a casing, 45 a shaft, a rotatable drum loosely mounted on said shaft, a spring surrounding said shaft, a friction brake, said brake mounted to frictionally engage said drum, a loosely mounted ferrule on said shaft, a movable clutch member on said ferrule, a fixed clutch member on said drum, said spring mounted between said friction brake and said movable clutch member, a handle attached to said ferrule, a catch on said casing to engage said handle and hold the clutch members out of engagement and compress said spring thereby exerting spring pressure on said brake, said spring forcing said clutch members into engagement upon detaching said handle from said catch.

55 In testimony whereof I hereby affix my 60 signature.

EARL C. WARNER.
